CLAIM

The ornamental design for a shopping bag, as shown and described.

DESCRIPTION

FIG. 1 is a perspective view of a shopping bag of my new design, showing the front and a side of the shopping bag in its closed position;

FIG. 2 is a side view of the shopping bag shown in FIG. 1 in its closed position; the opposite side of the view shown in FIG. 2 is a mirror image of the side view shown in FIG. 2;

FIG. 3 is another side view of the shopping bag shown in FIG. 1 in its expanded position; the opposite side of the view shown in FIG. 3 is a mirror image of the side view shown in FIG. 3;

FIG. 4 is a perspective view of the shopping bag shown in FIG. 1 from the front and one side of the shopping bag in its expanded position;

FIG. 5 is another perspective view of the shopping bag shown in FIG. 1 from the front and one side of the shopping bag with the elastic sides expanded to their fullest extent;

FIG. 6 is a perspective view of the shopping bag shown in FIG. 1 from the rear and one side of the shopping bag in its expanded position;

FIG. 7 is another perspective view of the shopping bag shown in FIG. 1 from the rear and one side of the shopping bag with the elastic sides expanded to their fullest extent;

FIG. 8 is a front view of the shopping bag shown in FIG. 1; a rear view of the shopping bag shown in FIG. 1 is a mirror image of the front view shown;

FIG. 9 is a top view of the shopping bag shown in FIG. 1 in its closed position; and,

FIG. 10 is another top view of the shopping bag shown in FIG. 1 with the elastic sides expanded to their fullest extent.
